MUFFLER CONSTRUCTION

Roy J. MacKenzie and Lucien L. Haas, Buffalo,
N. Y., assignors to Buffalo Pressed Steel Com-
pany, Buffalo, N. Y.

Original application December 8, 1934, Serial No.
756,638. Divided and this application Novem-
ber 30, 1935, Serial No. 52,387

7 Claims. (Cl. 181—41)

This invention relates to improvements in
mufflers or silencers of the kind which may be
used, for example, at the exhaust or intake of an
internal combustion engine. More particularly
5 this invention relates to improvements in sound
conducting passages or tuning tubes for use in
connection with such mufflers or silencers. This
application is a division of our pending appli-
cation Ser. No. 756,638 filed Dec. 8, 1934.

10 It has been found that in the construction of
mufflers or silencers, certain sound waves or
noises can best be eliminated by passing the
sound waves into a chamber which is connected
with another chamber by means of one or more
15 relatively small tubes of greater length than di-
ameter. Such tuning tubes have heretofore
been generally made of tubing welded to a baffle
separating the two chambers to be connected by
the tubing, and this construction, consequently,
20 involved considerable expense.

An object of this invention is to provide muff-
lers with sound conducting passages or tuning
tubes of improved and simplified construction.
Another object of the invention is to provide a
25 muffler with passages or tubes made entirely of
sheet metal and secured to the muffler by in-
expensive means. Another object of this inven-
tion is to provide a sound conducting passage
or tuning tube made of flat sheet metal formed
30 into tubular shape and having at the ends of
the tube tabs or extensions which may be welded
to a part of the muffler for holding the tuning
tube in place and at the same time holding the
metal of the tube in tubular form. Other objects
35 of the invention will appear from the following
description and claims.

In the accompanying drawing:

Fig. 1 is a fragmentary longitudinal, sectional
elevation of a muffler embodying this invention.

40 Fig. 2 is a transverse section thereof on line
2—2, Fig. 1.

Fig. 3 is a fragmentary transverse sectional
view thereof on line 3—3, Fig. 1, and on an
enlarged scale.

45 Fig. 4 is a plan view of a metal blank from
which a tuning tube of the muffler is formed.

15 represents the outer shell and 16 an inner
shell of a muffler and 17 and 18 are the end heads
or baffles of the muffler which extend inwardly
50 from the outer shell at the ends thereof and
which, in the construction shown, are provided
with tubular extensions or parts for the inlet and
discharge of exhaust gases into and out of the
inner shell or conduit 16. The muffler shown also
55 is provided with intermediate heads 19, 20 and

21 extending from the outer shell to the inner
shell of the muffler and forming between them
resonator or sound absorbing chambers 22 and
23 separated by the head or baffle 21. The cham-
ber 23 may receive sound waves from any suit-
able part of the muffler, for example, from the
inner conduit or shell 16 through openings or
apertures 24 therein and the other chamber 22
preferably has no direct communication with the
interior of the inner shell or conduit 16. The 10
muffler construction thus far described is herein
illustrated merely for the purpose of showing
how our invention may be applied to a muffler
and does not constitute a part of this invention,
since it will be readily understood that the tun-
ing tubes comprising this invention may be used
in connection with any two sound attenuating or
resonator chambers, wherever such chambers
may be formed in a muffler.

In order to produce certain silencing effects, it 20
is desirable under certain conditions to connect
the chamber 23 with the chamber 22 by means
of sound conducting tubes of materially greater
length than diameter to produce a bottle neck
resonator chamber. For this purpose, in accord-
25 ance with this invention, we provide a suitable
aperture in the baffle 21 and through the aper-
ture extends a sound conducting or tuning tube
embodiment this invention. A plurality of aper-
tures, each provided with a tube of this kind may 30
be provided. These tuning tubes are formed of
flat sheet metal, each bent into the form of a
tube 25 open at both ends and having the edges
of the metal sheet adjacent to the inner shell in
the form of a suitable joint which may be either 35
in the form of a butt joint or which may be
formed by overlapping the two longitudinal edges,
or which may be in the form of a seamed joint,
an overlapping joint being shown in the con-
struction illustrated.

40 The tubes 25 are assembled in a muffler by in-
serting the same through the perforations in the
baffles and are secured in place by tabs or parts
27 suitably connected with the tubes and secured
to an adjacent part of a muffler, such, for exam-
45 ple, as a shell. Preferably these tabs are formed
integral with the tubes and may be in the form
of extensions projecting beyond the ends of the
tubes. For example, the sheet metal, prior to
being formed into a tube, may have at the cor-
50 ners thereof, tabs or projecting parts 27 which
extend lengthwise beyond the ends of the body
portion of the tube and which, after the metal is
bent into tubular form, are bent toward an ad-
jacent portion of the muffler to which these tabs 55

- or projections may be secured. In the particular construction shown, these tabs or projections are bent to extend toward the inner conduit or shell 16 and are spot welded or otherwise suitably secured to the inner conduit or shell. It will be noted that when the tabs or extensions 27 are bent away from the axis of the tubular part 25, they will diverge from each other because of the fact that they are connected with the tubular part 25 at different portions of its periphery. The outer ends 28 of these tabs or extensions 27 may again be bent into any desired shape to facilitate the attaching of the same to another part of the muffler. When constructed in the manner described, the tabs, after they are secured to an adjacent part of the muffler, serve not only to securely hold a tube in correct position on a muffler, but also to hold the edge portions of the tube which form the longitudinal joint in correct relation to each other and thus to hold the tuning tubes in correct tubular form.

The construction described results in a tuning tube which is made entirely of flat sheet metal and which has a longitudinal joint which need not be welded or otherwise fastened. These tubes are, consequently, inexpensive to produce and by providing tabs or extensions for connecting the tubes to an adjacent part of a muffler, the cost of securing the tubes in place is greatly reduced since the tabs may be spot welded to the adjacent parts of the mufflers.

We claim as our invention:

1. A muffler including shells arranged one within the other and spaced apart, a transverse annular baffle extending between said shells and having an aperture, and a sound conducting tube arranged in said aperture and having projections extending laterally therefrom at opposite sides of said baffle and secured to one of said shells for holding said tube in correct relation to said baffle.

2. A muffler including shells arranged one within the other and spaced apart, a transverse annular baffle extending between said shells and having an aperture, and a sheet metal member having a portion thereof formed into a tube arranged in said aperture and having portions projecting beyond the ends of said tube and secured to one of said shells at opposite sides of said baffle.

3. A muffler including shells arranged one

within the other and spaced apart, a transverse annular baffle extending between said shells and having an aperture, and a sheet metal member having a portion thereof in the form of a tube and extending through said aperture, longitudinal edges thereof forming a joint extending lengthwise of said tube, and projections extending beyond each of the ends of the tube from said longitudinal edges and secured to an adjacent part of the muffler, whereby said tube is held in correct relation to the muffler and said edges are held in correct relation to each other at said joint.

4. A tuning tube for a muffler comprising a sheet of metal having a body portion in the form of a tube and having extensions of the longitudinal edge portions of the body portion, which are bent at an angle to said tube for securing to a part of a muffler.

5. A tuning tube for a muffler comprising a sheet of metal having a body portion in the form of a tube and having tabs extending beyond the ends of said body portion, said tabs being bent at an angle to the body of said tube for securing to a part of a muffler.

6. A muffler having a pair of shells and a baffle forming resonator chambers separated from each other by said baffle, said baffle having an aperture, a sound conducting tube extending through said aperture and comprising a metal sheet having a body portion of tubular form and having extensions projecting from the ends of said tubular body portion and secured to a shell of said muffler.

7. A muffler having a pair of shells and a baffle forming a pair of resonator chambers separated by said baffle, said baffle having an aperture, a sound conducting tube comprising a metal sheet having a body portion of tubular form and extending through said aperture, the longitudinal edges of said sheet forming a longitudinal joint of said tube, and tabs extending lengthwise beyond each longitudinal edge portion of said sheet and beyond the ends of said tube and extending at an angle to said tube, and means for securing the ends of said tabs to a shell of said muffler for holding said tube in correct position on said muffler and for holding said longitudinal edges in correct relation to each other at said joint.
